COMBINATION GRIDDE AND FRYER

Andrew S. Knapp, St. Louis, Mo., assignor to Knapp-Monarch Company, St. Louis, Mo., a corporation of Delaware

Application December 19, 1955, Serial No. 39,364

Term of patent 14 years

(Cl. D81—10)

Figures 2, 3, 4, and 5 are, respectively, top plan, front elevation, left side elevation, and right side elevation, views of the same.

I claim:

The ornamental design for a combination griddle and fryer, substantially as shown.
